CLAIM

We claim the ornamental design for a floating gems heart pendant, as shown.

DESCRIPTION

FIG. 1 is a Front View of the floating gems heart pendant.

FIG. 2 is a rear View of the floating gems heart pendant.

FIG. 3 is a side perspective view of the floating gems heart pendant.

FIG. 4 is a bottom view of the floating gems heart pendant; and,

FIG. 5 is a top view of the floating gems heart pendant.

The hexagons are indicative of gems floating and are not in a fixed position.
